UNITED STATES PATENT OFFICE.

JAMES J. KLEIN, OF NEW YORK, N. Y., ASSIGNOR OF ONE-HALF TO CONRAD R. SCHUMACHER, OF NEW YORK, N. Y.

TRACKER-BAR FOR AUTOMATIC MUSICAL INSTRUMENTS.

1,067,926.

Specification of Letters Patent.

Patented July 22, 1913.

Application filed June 28, 1909. Serial No. 504,889.

To all whom it may concern:

Be it known that I, JAMES J. KLEIN, a citizen of the United States, residing in the city of New York, borough of Bronx, county of New York, and State of New York, have invented certain new and useful Improvements in Tracker-Bars for Automatic Musical Instruments, of which the following is a full, clear, and exact specification.

- 10 My invention relates to pneumatically-operated musical instruments and has for its object to improve the construction of the tracker bar used in such instruments whereby the same tracker bar can be used for rolls 15 having perforations varying in size and of different spacing and at the same time admit a uniform amount of air to the player action pneumatic valves and other working parts.
- 20 Another object is to transpose the key in which the music is played by either raising or lowering the key from that in which the note sheet has been cut.

Another object is to enable the transposing device to act, also, as a part of the means whereby rolls of music with differently spaced lines of perforations may be played with the same tracker bar without additional parts.

30 Another object is to furnish a device which shall be small and compact, shall have few parts, and shall be self-contained.

Another object is to improve the means of shifting a change slide used in such tracker bar as one of the means whereby the same is adapted to play rolls of music differently perforated.

Another object is to provide a tracker bar with a shiftable tube head in combination 40 with an adjusting and indexing feature, thereby forming a transposing device which will play up or down the scale, increasing or decreasing the pitch by semi-tones, thus playing the note sheet in a higher or lower 45 key while playing the instrument without the necessity of adding additional holes in the face of tracking bar or shifting the tracker face for transposing purposes.

These and other objects which will appear 50 as the description proceeds, I accomplish by

the devices hereinafter described and illustrated in the accompanying drawings, wherein—

Figure 1 is a face view of a tracker bar provided with two rows of channels adapted to play with note sheets having fifty-eight, sixty-five, or eighty-eight lines of perforations. Fig. 2 is a top view of the tracker bar and tube head partly in section, the section being taken on the line 2—2 of Fig. 1, through the sixty-five line of perforations. Fig. 3 is a vertical longitudinal section on the line 3—3 of Fig. 10, the change slide being illustrated in full lines. Fig. 4 is a rear view of the tracker bar, parts being shown in section on the line 4—4 of Fig. 10. Fig. 5 is a view similar to Fig. 2, taken on the line 5—5 of Fig. 1, through the eighty-eight line of perforations. Fig. 6 is a face view of a form of tracker bar having a single row of perforations. Fig. 7 is a top view, partly in section, on the line 7—7 of Fig. 6, illustrating an adjustable tube head forming a transposing device. Fig. 8 is a diagrammatic view illustrating various modified forms of mouthpiece openings in tracker bar face which may be used to secure uniformity of suction when a double line of channels is employed in the tracker bar. Fig. 9 is an enlarged detail sectional view on the line 9—9 of Fig. 12, illustrating the means for adjusting the transposing device. Fig. 10 is an enlarged transverse section of the tracker bar on the line 10—10 of Fig. 1, illustrating one of the eighty-eight line of channels in playing position. Fig. 11 is an enlarged detail view, partly in section and partly broken away, illustrating the top of the right end of the tracker bar (Fig. 1). Fig. 12 is an enlarged detail view of the adjusting means for the transposing device. Fig. 13 is a similar view of a modified form of the adjusting means of Fig. 12. Fig. 14 is a rear elevation of the tube head broken away and partly in section. Fig. 15 is a top view of a tracker bar and tube head, partly in section, wherein the adjustable tube head serves as a combined transposing device and change slide. Fig. 16 is a vertical section view of the tracker bar and tube head, partly in section, illustrating the change slide and transposing device.

cal longitudinal section of the complete device on the line 16—16 of Fig. 15, showing the rear of the tracker bar in full lines and illustrating the channels therein as staggered. Fig. 17 is a diagrammatic view illustrating features of construction of the channels in the tracker bar. Fig. 18 is a tube head adjusting-device adapted to the constructions of Figs. 15 and 16.

10 Rolls of music as now commercially supplied for player pianos and piano players are differently perforated, some having sixty-five lines of perforations transversely and some having eighty-eight. The perforations in these different rolls are not of the same width, but are so much wider in those rolls having sixty-five perforations than in those having eighty-eight perforations that the former require a wider roll than the latter. The openings in the tracker bar conform in width to the perforations in the roll, and tracker bars which are constructed to receive a sixty-five roll will not operate with an eighty-eight roll. It is therefore of advantage that the tracker bar shall be so constructed that it will play with either roll of music and that by reason of the differing width of the perforations in such rolls, and the necessity that the opening in the tracker bar shall be of the same width, and in order to secure uniform and the best results, that a uniform amount of air shall be admitted to the pneumatics and other working parts of player action from these differing openings in the tracker bar. It is also probable that rolls will be supplied having perforations differing in spacing and dimension from those heretofore supplied and it is important that devices adapted to play with various spaced rolls should be constructed upon a principle of such flexibility that it will easily adapt itself to all spacings.

Uniform air control.—In the principal form of my improved tracker bar as illustrated in Figs. 1, 2, 3, 4, 5, 9, 10, and 11, the tracker bar 1 is provided with two rows of channels 2, 3. The upper row contains sixty-five channels 2, and the lower row eighty-eight channels 3, designed for music rolls having these respective perforations. These channels are arranged in the face of the tracker bar to register with music and are of different size, the channels 2 being larger than the channels 3. At the rear, however, they are of uniform size and are symmetrically disposed with their sides in the same vertical planes as seen in Fig. 4, illustrating the rear of the tracker bar. Here, however, the row containing the channels 3, which are intended to be eighty-eight in number, is wider than the other row, and extends beyond the row containing channels 2, which are sixty-five in number, and will contain eleven more channels at one end and

twelve more at the other end. As drawn, 65 only eighty-six channels are illustrated, wherefore the row of channels 3 only projects ten channels at the left over channels 2.

To produce an even spacing of the two rows of channels at the rear of the tracker bar, the channels 2, which, though less in number occupy a greater width at the face of the tracker bar, are caused to converge toward the rear as seen in Fig. 2, and the channels 3 are caused to diverge toward 75 the rear, as seen in Fig. 5. As both rows of channels control the inflow of air to the same set of perforations and player pneumatics, it is important to secure the best results that a uniform amount of air shall be admitted 80 to said parts from channels 2, as well as from channels 3. Normally, channels 2 being of greater area in cross-section, would, if of the same diameter throughout, admit 85 more air than the smaller channels 3, and this I propose to control by constructing the face or front opening of the channels 2 in some one of the various forms illustrated in Fig. 8, where, although the cross-sectional area is reduced so that it shall approximately conform to that of channels 3, the full width of the channel at some part thereof is preserved so that it shall register with the perforations in the roll. I conceive the fish-tail form of opening, which I designate 95 4, as being useful for the purpose.

I desire to admit a uniform amount of air through the channels 2 as well as the channels 3 for the reason that as the bleed holes in both single and double valve pneumatic 100 systems in common use are proportioned to the size of the openings in the tracker bar, one size of bleed hole must bleed into the vacuum chamber whatever air remains in the tracker tube after the air admitted has 105 performed its function, *i. e.*, striking the valve actuating diaphragms. If the rows of tracker openings are of different sizes, the bleed would be rapid for 88 note or smaller 110 tracker openings and slacker for the 65 note or larger tracker openings, due to difference in amount of air admitted through smaller or larger tracker openings. It follows that the different rows of openings in the tracker bar should be brought as nearly to a uniform 115 size as possible in order that the best results in playing should be accomplished.

By reason of the variable spacing between the two rows of channels in the face, and in order to produce a uniform arrangement at 120 the rear and have a substantial amount of material between the channels at the rear of the tracker-bar and that the distance from front to rear shall be of minimum dimensions, I construct said channels so that their 125 width, by which I mean their horizontal dimensions, shall diminish gradually throughout the slanting portion, as seen best in the

enlarged view (Fig. 11), and in the dia-
grammatic view (Fig. 17). Their depth,
however, by which I mean their vertical
dimensions, is increased throughout this
5 slanting portion, as seen clearly in enlarged
views (Figs. 9 and 10), and thereby their
cross-sectional area is substantially uniform.
In order to avoid irregularity in the size of
10 the channels at the rear, which would occur
if the slanting portion of the channels ex-
tended to the rear of the tracker bar, I con-
struct the channels with straight termina-
5, the rear being of uniform size.

In the enlarged diagrammatic view (Fig.
15 17), I have shown, somewhat exaggerated,
this feature in the right-hand channel 6, and
it will be seen that small shoulders 7 are
formed at the junction of the slanting portion
20 of such channel with the straight ter-
minals thereof, such shoulders being the re-
sult of the junction of the uniformly sized
straight rear channels 5 with the inclined
portions 6 of the channels. From the
25 tracker bar rearwardly, both sets of chan-
nels operate through the same tubes, and
uniformity of suction will exist. I secure
the same uniformity in the different rows of
channels in the tracker bar by the use of the
30 irregularly-shaped openings as 4 (Fig. 8),
and by the uniformity in cross-sectional
area of the slanting portions of the channels,
and the provision of the straight terminals.

Transposing device.—I have provided
means whereby, without the use of addi-
35 tional parts other than adjusting devices,
the key may be raised or lowered one or
more notes as desired, and this I accomplish
by making the tube head adjustable. In
Figs. 6 and 7 I have illustrated a simple
40 form of device wherein the tracker bar 8 is
formed with a single row of channels which
are wide and shallow at front and deep and
narrow at rear. The tube head 9 slides lon-
gitudinally of the tracker bar and is ad-
45 justed by a block 10, which is attached to it
in any suitable way, as by screws 11, and
slides in a slot 12 in the tracker bar. The
block has a fingerpiece 13, by which it may
be moved, and which, also, by means of the
50 arrow (Fig. 6), serves as a pointer to indi-
cate upon the scale of the tracker bar the ex-
tent of adjustment required. I may also
employ the same transposing device in a
tracker bar containing two rows of channels,
55 and when so employed it will act, when de-
sired, not only as a transposing device, but
also as a changing device, whereby either
row of channels may be made to play at will
and music adapted to either row may be
60 transposed. A device embodying this con-
struction is illustrated in Figs. 15 and 16
and the tube head employed therewith is
shown in detail in Figs. 9, 10, and 14. In
this form the tracker bar 1 is of the con-

struction of Figs. 1 to 5, with the excep- 65
tion that the channels are staggered at the
rear of the tracker bar, as seen in Fig. 16,
and are not symmetrically arranged, as in
Fig. 4.

The tube head 9 fits snugly against the 70
rear of the tracker bar and is formed with a
series of rectangular chambers 14 in its face
(Figs. 10, 14), into which open the oval tubes
15, which may be provided with round 75
terminals 16 for easy attachment to the flexible
player-action tubes. The tubes employed
are made oval by reason of the larger num-
ber that may be located in the same width,
and they are bent at their lower ends, as at
17, for easy attachment to the flexible tubes. 80
The material between the channels in the
same row in Fig. 16 should be not less than
the width of the channels, and if anything,
should be slightly wider than the air chan-
nels, and the air chambers 14 are of uniform 85
width, so that when these chambers are in
position to admit air from one set of chan-
nels, the opposite set, owing to the staggered
arrangement, will be closed.

The means for securing the adjustment of 90
the tube head may be of the simple form
illustrated in Figs. 6 and 7, but owing to
the fact that two rows of channels are em-
ployed and accuracy of adjustment is re-
quired, I prefer to employ an adjusting de- 95
vice of the kind illustrated in Fig. 18, where
a combined fingerpiece and pointer 60 is
fixed upon a shaft 61, which extends from
front to rear of tracker bar and is journaled
in a boss 62, formed upon the top of the 100
tracker bar, and at its rear end carries fixed
thereto, an arm 63, slotted at 64, to receive
a pin 65 projecting rearwardly from the
tube head. The pointer 60 indicates upon a
double scale with right and left hand grad-
uations, the inner graduations representing
the position of the pointer when the sixty-
five music is playing and the necessary
movements of the pointer to transpose
higher or lower by semi-tones, and the outer 105
row of graduations represent the position
of the pointer when the eighty-eight music
is playing and the necessary movements of
the pointer to transpose higher or lower by
semi-tones. This is a desirable and practi- 110
cable way of adjusting the tube head, but
other modes might be employed, as my in-
vention does not alone reside in the means
of accomplishing such adjustment.

I have in the foregoing description of the 115
form of device illustrated in Figs. 15 and
16, referred to Figs. 9, 10, and 11, as show-
ing the construction of the tube head ad-
justing-device in greater detail than Figs.
15 and 16. The said Figs. 9, 10, and 11, 125
however, show a slide 39, such as is illus-
trated in my Patent No. 925,777, dated June
22, 1909, and which is designed to close one

or the other sets of channels at the rear of the tracker bar according to adjustment, whereas the construction of Figs. 15, 16, is designed to eliminate such change slide and 5 to transfer its function to the tube head. The presence of the change slide in the construction of Figs. 9, 10, and 11, causes no change in the construction or operation of the tube head adjusting-devices there illustrated, changes only being made in the indexing, and these views illustrate the device 10 of Figs. 15, 16.

The presence of the slide 39, when it is used, however, does not prevent the adjustment 15 of the tube head as a transposing device, and in Figs. 1 to 5 and 9 to 14, I have illustrated a construction employing such slide and providing for the adjustment of the tube head to transpose the music. Here 20 I have improved the means employed to adjust the change slide, employing for that purpose a handle and pointer 40 (Fig. 1), on the face of the tracker bar at the end opposite the transposing pointer indicating 25 upon a scale 41 on the adjacent face of the tracker bar and fixed upon a shaft 42, which passes rearwardly through a hole in the tracker bar and at its rear end carries a cam 43, which is located within a recess 44 in 30 the rear of the tracker bar. Upon the face of the slide 39 and extending within the recess 44, are two parallel flanges 45, which fit the cam 43 snugly, but have play in the recess 44. As the cam 43 is turned, the slide 35 39 will be moved longitudinally to correspond and locked in position, so that when the tube head is moved the adjustment need not be disturbed. Only a slight motion is necessary to adjust the slide and therefore 40 the recess 44 need not be large.

Other forms of adjusting devices which might be employed are illustrated in Figs. 12 and 13. In Fig. 12 a combined handle and pointer 18 is located upon a recess 19 in 45 the face of the tracker bar near the end thereof and indicates upon a scale 20 formed upon the face of said tracker bar. This scale is single, with right and left hand graduations, the graduations and figures at 50 the right of the normal position of the pointer indicating the proper position of the tube head with respect to higher notes, the index and figures on this side indicating the number of semi-tones higher it is possible to play the note sheet, and the graduations and figures upon the other side indicating such position with respect to the other or lower notes, the index and figures here indicating the number of semi-tones 55 60 lower in which the music may be played. The lever and index 40, 41, 42, at lefthand end of tracker bar (Fig. 1), are used for setting change slide for playing sixty-five (65) or eighty-eight (88) tracker face open-

ings. The handle 18 is fixed upon the forward end of shaft 21, which extends rearwardly through a hole in the tracker bar and at its rear end carries a toothed segment 22 firmly fixed thereto and gearing into a similar toothed segment 23 fixed upon a shaft 70 24 located upon the upper face of the tube head and swiveled in a boss or lug 25 projecting upwardly therefrom. At its rear end this shaft has an arm 26 fixed upon it, which is slotted at 27 and a pin 28 projecting rearwardly from the tube head enters said slot and converts the rotary motion of the arm into a longitudinal movement of the tube head. 75

In Fig. 13 a knurled knob or disk 29 is located upon the face of the tracker bar at either end and is provided with a pointer indicating upon a scale or index as before. This is fixed upon a shaft 30, which extends rearwardly through a hole in the tracker 80 bar and also through a slot 31 in the tube head. Situated interiorly of the tube head and at the front thereof in a recess milled in the rear of the tracker bar proper is a disk 32 fixed upon the shaft 30 and provided 85 with a pin 33. This pin takes into a slot 34 of a swinging arm 35, which at one end is swiveled to a boss 35 formed upon the top of the tube head and at the other end is swiveled to a link 36, which is swiveled at 37 90 to a bracket 38, extending downwardly from the tube head. The slide 39 controls the tracker bar channels and whichever set is in use will permit air to pass through the slide to the air chambers 14 in the tube head and 100 thence through the tubes 15, 16, as both sets of the openings at the rear of the tracker bar, as well as both sets of perforations in the slide are of uniform size. As these openings at the rear of the tracker bar are in different horizontal planes, the chambers 14 in the tube head are made deep enough (in vertical dimension) to cover either set which may be playing. The width of the chambers 14 (horizontally), is such that they will 105 register with any of the perforations in the slide 39, but will not admit air from the perforations on each side in the other row. The depth of these chambers rearwardly is large enough to obtain uniform flow of air 110 at this point in the tube head. To obtain, therefore, a transposition of music without any liability of admitting air through the closed channel, the index 20 (Fig. 12), is made double, to wit, it has two scales, one 115 reading each way from the central position, one row indicating the extent of transposition and proper halting place on the index higher or lower by semi-tones when playing with music having certain perforations, and 120 the other row indicating likewise for music differently perforated.

The tube head is maintained in position

by suitable means, as, for instance, by flat springs 46 (Figs. 10, 11), attached by screws 47 at the rear side of walls 48, which are integral with the tracker bar, and these 5 springs press the tube head forwardly upon the change slide with sufficient force to keep the joints air-tight at this point.

In the construction of the tracker bar I have made improvements which tend to 10 give a tighter joint and prevent leakage of air consisting in the fins 49, 50, at the front and rear of the channels respectively. The said fins are integral with the bottom plate by which I mean the material closing the 15 rear part of the tracker bar and which has perforations corresponding to the channels. This bottom plate is shown in dotted lines in Fig. 10. The said tracker therefor as shown comprises as integral parts the tracking 20 face, rearwardly extending fins, central partition, bottom plate, forwardly extending fins and rearwardly extending walls, and such construction I prefer but do not deem essential to my invention. These channels 25 are closed by lids 51, which fit so snugly as to maintain their position, and if the channels were open on the outside at the ends, there would be danger of leakage, which I overcome by closing the channels at those 30 points by said fins, which are integral with the tracker bar. A packing 52 of thin rubber cloth or cloth and shellac may, if desired, be placed inside of these lids in the position indicated by the heavy lines on 35 the inside of said lids (Figs. 9 and 10).

What I claim is:

1. In a tracker bar having a plurality of sets of channels of different widths at the face of said bar, each of the wider channels 40 conforming to the widths of the perforations in the roll through part of its area, and having a portion thereof of less width.

2. A tracker bar having a plurality of sets of channels of different widths at the 45 face of said tracker bar, each of the wider channels conforming in part to the widths of the perforations in the roll, and partly reduced in area at face of the tracker bar, whereby the cross-sectional areas of the 50 two sets of channels are substantially uniform.

3. A tracker bar having channels and a transposing device consisting of a tube head located adjacent said tracker bar and means 55 for shifting the same longitudinally with relation to the tracker bar whereby the channels in the tube head may be caused to register with the next adjacent channels in the tracker bar either higher or lower in 60 key comprising a scale upon the face of the tracker bar, a movable finger-piece, located adjacent said scale so as to move thereover, and an operative connection from said finger-piece to the tube head.

4. A single tracker bar having a plurality 65 of sets of channels, a longitudinally-adjustable tube head located adjacent said tracker bar provided with transverse channels, said channels being substantially parallel with the face of the tracker bar and means for 70 adjusting the tube head longitudinally with respect to the tracker bar to bring the channels in the tube head into register with the adjacent channels in each set in the tracker bar, either higher or lower in key. 75

5. A single tracker bar having two sets of channels with openings of different spacing at the front, a tube head longitudinally adjustable with respect to said tracker bar, provided with transverse channels and act- 80 ing as a combined tube head, transposing device and change slide, means for adjusting said tube head whereby the channels in said tube head may be caused to register with either set of channels in the tracker bar 85 as a change slide, and the channels in the tube head may be caused to register with adjacent channels in either set of channels in the tracker bar either higher or lower as a transposing device. 90

6. A single tracker bar having two sets of channels of different spacing at the face and of similar spacing and size at the rear, the channels at the rear being staggered, a tube head longitudinally adjustable with respect 95 to the tracker bar, having a set of tubes and a row of chambers into which the tubes open, each chamber extending across both rows of channels and corresponding in width and spacing to the rear openings in 100 said channels, and means for adjusting the tube head.

7. A tracker bar having a plurality of sets of channels, a longitudinally-adjustable slide adapted to open one set of channels according to adjustment, and means for adjusting the same, a tube head longitudinally adjustable, and provided with air channels, 105 adapted to register with said open channels, and means for adjusting said tube head 110 whereby the air channels therein may be caused to register with the adjacent open tracker bar channels either higher or lower in key.

8. A tracker bar having two sets of channels of different spacing and size at the face and of the same spacing and size at the rear, and both sets symmetrically disposed with relation to each other at the rear, a longitudinally-adjustable slide at the rear of the 120 tracker bar, having a plurality of sets of openings of like size and spacing but staggered with respect to each other, and means for adjusting said slide, and a tube head longitudinally adjustable with respect to the 125 tracker bar.

9. A tracker bar having a plurality of sets of channels, an adjustable slide adapted

- to open one set of said channels, and means for adjusting the same, an adjustable tube head having tubes adapted to register with said open channels and means for adjusting the same whereby said tubes may be brought into register with adjoining channels, either higher or lower in key.
10. A tracker bar having a plurality of sets of channels and an adjustable slide adapted to open one set of said channels, and means for adjusting and holding the same comprising a fingerpiece upon the tracker bar, a cam rotatably connected with said fingerpiece and flanges upon the slide embracing said cam.
11. A tracker bar having channels, a tube head longitudinally adjustable having air openings adapted to register with said channels and means for adjusting said tube head comprising a fingerpiece on the tracker bar, a rotatable gear operatively connected thereto, a second gear meshing therewith and rotatably mounted upon the tracker bar, a swinging arm operatively connected to said second gear and having a sliding connection with the tube head.
12. A tube head comprising a series of parallel adjacent air chambers, a tracker bar having channels, means for connecting said channels and chambers, a connection from each of said chambers to the pneumatics, including a tube oblong in cross section opening into each of said chambers, whereby the capacity of the tube at the point of connection is increased without removing an undue amount of material from the tube head.
13. A tracker bar having channels, each constructed at the face and rear with straight terminals and connected by an angular portion, the side walls of which converge from front to rear and the top and bottom walls of which diverge from front to rear.
14. A tracker bar comprising a tracking face, a central wall, channels disposed on either side of said wall, a bottom plate perforated for said channels, fins extending rear and front from the said face and bottom plate forming part of the outer walls of said channels, lids closing said channels, walls extending rearwardly from the bottom plate and a tube head between the same, and means on said walls for retaining said tube head in position and permitting the same to move longitudinally.
15. A tracker bar provided with channels and fins integral with the body of the tracker bar closing the outer sides of said channels at their forward and rear parts, and a lid resting snugly against the outside of said channels and closing the balance thereof.
- In witness whereof, I have hereunto set my hand in the presence of two subscribing witnesses.
